OF DALLAS, TEXAS.

BEST AVAILABLE COPY MODEL-DISPLAY STAND.

1,283,369.

Specification of Letters Patent. Patented Oct. 29, 1918.

Application filed January 18, 1918. Serial No. 212,423.

To all whom it may concern:

Be it known that I, CLAUDE B. TYLER, a citizen of the United States, residing at Dallas, in the county of Dallas and State of

5 Texas, have invented certain new and useful Improvements in Model-Display Stands, of which the following is a specification.

This invention relates to new and useful improvements in model display stands.

10 There has been some development in this art in the nature of a stand having a back ground with an opening outlined to represent the figure of a person. By placing a piece of fabric against the rear side of the 15 back ground said fabric is displayed through the opening thus representing the outlined person as wearing a suit made of said fabric. However, such back grounds have not been made changeable or interchangeable.

20 nor has any covering been provided for the open space, and the entire display has had a more or less flat and inartistic appearance. The idea involved in this invention is to provide a back ground in the form of a 25 sheet or panel which may be readily placed in a display frame and to have a portion or portions of said sheet transparent and outlined to represent clothing or other articles. Also to arrange for supporting fabric in 30 contact with the under or rear side of the transparent portions whereby said fabric will be displayed therethrough. This permits of an attractive scene being painted as a back ground around said transparent portion, and by changing sheets a variety of 35 displays may be had. Further it is proposed to dispose the sheet so as to give it a slight curve transversely and by employing celluloid or similar material and painting the 40 back ground and an outline of a figure on the rear side, the display is given more or less sheen, and the figure and back ground may be observed from various angles with a very pleasing effect.

45 In carrying out the invention a frame is disposed on a base to form a stand. A sheet having a back ground and an outlined transparent portion is placed in the frame. A back member is provided and the fabric 50 is draped over, this back member which is afterward clamped into the frame against the sheet, whereby the fabric is displayed through the transparent portion. Other details may be included.

55 The invention will be more readily under-

stood from a reading of the foregoing specification and by reference to the accompanying drawings, in which an example of the invention is illustrated, and wherein—

Figure 1 is a face view of a stand constructed in accordance with this invention,

Fig. 2 is a vertical sectional view of the same, indicating in dotted lines the back member swung out to receive the fabric,

Fig. 3 is a transverse sectional view, and 65

Fig. 4 is a partial rear elevation.

In the drawings the numeral 1 designates a base of suitable construction on which a vertical frame 2 is fixed. This frame may have a slight inclination from the perpendicular so as to incline away from one observing it. The frame is formed like an ordinary picture frame so as to receive from its rear side a sheet 3. The upper and lower rails 4 of the frame are bowed outward so 70 as to give a slight transverse curve to the frame, and when the sheet is placed into the frame it will also be bowed outward.

As shown in Fig. 1 the sheet has a back ground and I prefer to produce the back 80 ground on the rear side of this sheet any suitable way. The sheet is preferably formed of celluloid or some other material, and an outlined portion 5 is produced which is transparent. It would be possible to form 85 the outlined portion of a transparent material and the remainder of the sheet of an opaque material, but I prefer to use a single sheet. Hooks 6 may be provided at the rails 4 to receive and support the sheet which is 90 flexible enough to be bowed in order to place it under said hooks.

A back member 7 is provided and bowed transversely to form to the curvature given 95 the sheet 3. A pair of hinged links 8 connected with the base of the frame and the base of the member 7 support the same when it is swung out of the frame and act to guide it into place. An upright post 9 is mounted on the rear of the base and has a seat 10 at 100 its upper end receiving a transverse bar 11 on the back member when said member is swung out of the frame as is shown in dotted lines in Fig. 2. With the back member in the position shown in Fig. 2 a piece of 105 fabric or goods 12 may be readily draped over said back member and arranged as desired. With the fabric on said member the latter is swung into the frame and spring clamps 13 are engaged under clips 14, where- 110

by the member is pressed into the frame and the fabric held in close contact with the rear side of the sheet 3.

It will be seen that the fabric is displayed through the outlined transparent portion 5 and owing to the curvature or bow of the sheet one does not have to stand directly in front of the display in order to obtain a satisfactory view, but they observe the model 10 in passing and from various angles. The glazed surface gives the entire display a more natural appearance as the fabric will be blended into the back ground and the sharp contrast which might otherwise be 15 had between a soft piece of goods and a dull back ground will be eliminated. When it is desired to change the fabric or the sheet it is apparent that either may be accomplished expeditiously.

20 The foregoing description and illustration clearly express the invention, but it is to be understood that said illustration is merely an exemplification and the invention may be carried out in various ways.

25 What I claim is,

1. In a model display device, the combination with a base and a frame member mounted on the base, of a sheet removably disposed in the frame and having an outlined transparent portion immediately surrounded by 30 a back ground portion, a back member constructed to support a piece of fabric in contact with the rear side of the sheet, whereby said fabric is displayed through the transparent portion of said sheet and to fit into 35

the frame, means for fastening the back member in the frame, and a support mounted on the base for receiving and supporting the back member when the latter is removed 40 from the frame.

2. In a model display device, the combination with a base, of a frame mounted on the base and bowed transversely, a sheet disposed in the frame and bowed transversely, 45 said sheet having an outlined transparent portion surrounded by a back ground, and a back member curved transversely for supporting a piece of fabric in contact with the rear face of the sheet.

3. In a model display device, the combination with a base and a frame mounted on the base, of a sheet of transparent material mounted in the frame and having a transparent outlined portion immediately surrounding said outlined portion, said sheet being removable from the frame, a back member constructed to support a piece of fabric in contact with the rear face of the sheet whereby said fabric is displayed 60 through the outlined portion thereof, a hinge device connecting the back member with the base of the frame, a support receiving the back member when the latter is swung out of the frame and coöperating 65 with the hinge device in holding and positioning said back member, and means for clamping the back member in the frame.

In testimony whereof I affix my signature.

CLAUDE B. TYLER.
